(57) **CLAIM**

The ornamental design for a flat panel display stand base with negative ion generator, as shown and described.

DESCRIPTION

FIG. 1 is a front view of a flat panel display stand base with negative ion generator;

FIG. 2 is a back view thereof;

FIG. 3 is a top view thereof;

FIG. 4 is a bottom view thereof;

FIG. 5 is a left view thereof;

FIG. 6 is a right view thereof; and,

FIG. 7 is a perspective view thereof.

The broken lines depict portions of the flat panel display stand base with negative ion generator that form no part of the claimed design.
